United States Patent Office.

LEWIS ALLEN, OF BERKELEY SPRINGS, WEST VIRGINIA.

Letters Patent No. 66,441, dated July 9, 1867.

IMPROVED BROOM-HEAD.

The Schedule referred to in these Letters Patent and making part of the same.

TO ALL WHOM IT MAY CONCERN:

Be it known that I, LEWIS ALLEN, of Berkeley Springs, in the county of Morgan, and State of West Virginia, have invented a new and improved Broom-Head; and I do hereby declare the following to be a full and exact description of the same, reference being had to the accompanying drawings, which are made part of this specification, and in which—

Figure 1 is an elevation.

Figure 2 is longitudinal section.

Similar letters of reference indicate corresponding parts in the two figures.

The socket of the broom-head is made of leather pierced for the passage of the sewing-twine, and with a confining-band, also pierced, and retained on the socket by grooves in the latter. In the drawings—

A is the broom-head, and B a cross-piece fastened to the handle and enclosed by the butts of the broom-corn or other material of which the broom is composed. C is a leather socket having extensions D with depressions d to receive the band E which confines the corn. The socket C and the band F are pierced with holes through which passes the twine which secures the broom corn in the socket, and maintains it in its flattened shape.

The mode of operation is as follows: The end of the handle A, with its cross-piece B, being placed within the socket, the butts of the broom-corn are stuck into the latter on each side of the cross-piece until a sufficient quantity is placed therein. The broom-corn in this condition will be nearly a round bunch, around which the band E is slipped, confining it within a given diameter at this point. A pressure is then brought upon the broom which flattens it, and it is sewn from the side by the twine passing through the openings g g in the socket C, and in the band E. The broom-head will outlast a great many fillings of corn, looks well, is light, substantial, and cleanly.

Having described my invention, what I claim as new, and desire to secure by Letters Patent, is—

The handle with its cross-piece B pinned in the mortise at right angles to the handle, in combination with the perforated leather socket C and perforated leather band E, retained by the recesses d in the extensions D of the socket, substantially as described.
